UNITED STATES PATENT OFFICE.

WILLIAM H. DOBLE, OF QUINCY, MASSACHUSETTS, ASSIGNOR, BY DIRECT AND MESNE ASSIGNMENTS, OF THREE-FOURTHS TO HENRIETTA W. DOBLE, OF QUINCY, MASSACHUSETTS, AND ONE-FOURTH TO PNEUMATIC SCALE CORPORATION LIMITED, OF QUINCY, MASSACHUSETTS, A CORPORATION OF MAINE.

KNOCKDOWN SHIPPING CASE OR BOX.

941,014.

Specification of Letters Patent. Patented Nov. 23, 1909.

Application filed December 24, 1908. Serial No. 469,940.

To all whom it may concern:

Be it known that I, WILLIAM H. DOBLE, citizen of the United States, residing at Quincy, in the county of Norfolk and State of Massachusetts, have invented certain new and useful Improvements in Knockdown Shipping Cases or Boxes, of which the following is a specification, reference being had therein to the accompanying drawings.

10 One of the large items of expense to manufacturers of many kinds of goods is the cost of shipping cases. It is the general custom to make the shipping cases of wood, and in most instances these cases after they have 15 been once used are good for nothing except to be knocked to pieces for kindlings. The item of expense for such packing cases alone in case of large manufacturers amounts to many thousands of dollars in the course of 20 a year.

The object of my invention is to provide a shipping case which shall be both strong and durable and which can be folded up into compact form to be returned to the 25 shipper after the goods have been unpacked by the receiver so that the shipping case can be used repeatedly. The expense for returning the folded empty box to the shipper is much less than the cost of a new box of 30 the ordinary construction as of wood, and in this way a very great saving is made in the course of a year.

In the preferred form of construction embodying my invention the box is made of 35 corrugated sheet metal of somewhat the same general form as knock-down cartons, the four sides being hinged together so as to fold instead of being creased to fold as in the ordinary folding carton and being provided 40 with four end flaps at each end hinged to the ends of the respective side panels; that is, each of the four sides is provided with an end flap at each end hinged thereto so as to fold over and close the ends and having 45 means for firmly locking the ends to secure them instead of having them glued or of having the slot and tongue connection which is common with paper cartons. It is also preferred to have the corrugations of the 50 plates formed in the different end flaps which lap onto each other made to coöperate with

each other in such manner that they will nest together.

The invention will be fully understood from the following description taken in connection with the accompanying drawings, and the novel features will be pointed out and clearly defined in the claims at the close of the specification.

In the drawings,—Figure 1 is a perspective of a portion of a box embodying my invention showing a portion of the body of a box and the end closing flaps for one end, the box being squared out and filled and ready for folding the end flaps. Fig. 2 is a perspective showing the complete box, the bottom being entirely closed, the two end flaps for the top being folded; one of the side flaps being partially folded, and the other side flap being unfolded. Fig. 3 is an end view of the box when closed and locked. Fig. 4 is a section on line 4—4 of Fig. 3. Fig. 5 is a section on line 5—5 of Fig. 3. Fig. 6 shows the use of a seal in connection with the locking bar. Fig. 7 is a section on line 7—7 of Fig. 6. Fig. 8 is a section of the box showing the four sides and bottom.

Referring to the drawings,—the body of the box comprises four plates A, B, C and D hinged together at their proximate edges in such manner that it may be knocked down and the four sides may be folded flat somewhat after the manner of the body of an ordinary collapsible carton. The hinge joints may be made in any suitable manner, that preferred being as shown, that is—each edge of each of the panels or sides A, B, C, D is formed with a series of curls 1 which coöperate with a series of curls on the proximate edge of the adjoining panel through all of which the hinge wire passes for uniting them together. Hinged to the upper end of each of the side panel plates A, B, C, D, respectively are the flaps E, F, G, H, and hinged to the lower end of each of the plates A, B, C, D, are end closing flaps similar to the end closing flaps E, F, G, H. The end flaps F, H, which, if the box is made oblong in cross-section, are preferably hinged to the narrower sides B, D, of the box are each made to extend half way across the end of

the box so that when the end flaps F, H, are folded, the edges will meet without overlapping each other as is common with cartons. The side flap G then folds over on top of the flaps F, H, and the flap E folds outside of the flap G.

Each of the plates forming the sides and the end flaps is preferably formed with corrugations both longitudinally and transversely which may be made by stamping the metal. The object of these corrugations is to strengthen and stiffen the plates so that with a given thickness of sheet metal of which the box is formed the greatest amount of rigidity and strength may be obtained. The preferred form of these corrugations is that they should form a series of cup-shaped depressions with sloping sides and preferably with flat bottoms and flat topped elevations between the depressions. In order also that the end closing flaps which overlap each other when the carton is set up and the end flaps are closed may fit closely together, it is desirable that the corrugations in the flap G which overlaps the flaps H, F, shall be formed in such manner as to nest therein and the corrugations in the flap E which overlaps the flaps G shall be formed so as to nest in the corrugations of the flap G as shown in Figs. 4 and 5. To this end the bottoms 2 of the depressions in the end flaps H, F, are made of greater diameter than the bottoms of the depressions 21 in the side flap G, and the bottoms of the depressions 22 in the side flap E which is the last to be folded are of less diameter than the bottoms of the depressions in the flap G as clearly shown in Figs. 4 and 5. Preferably the end flaps H, F, are formed with a border 3 around the three sides which are hinged somewhat higher than the tops 4 of the corrugations intermediate the borders 3, and the side flap G is similarly formed with a border 5 at a higher elevation than the tops 6 of the intermediate corrugations and the side flap E is formed with a border 7 of a higher elevation than the tops 8 of the intermediate corrugations. The purpose of having these raised borders is to form a firm abutment for the inclined sides of the depressions or corrugations at their outer edges to resist lateral distortion of the flaps and hold them a little more rigidly together.

In order to lock the end closing flaps together after they are folded, I provide a slot and staple construction for interengaging and locking the flaps. As shown in the drawings the end flaps H, F, are provided with staples 9 projecting upwardly therefrom, and I provide the side flaps E, G, with slots 10 through which the staples 9 project when the side flaps E, G, are closed. On each end of the outer flap—that is, the flap E when they are all closed—is pivoted a locking bar 11 pivoted to the flap E at

12, this locking bar having at each end hooks 13 which are adapted to engage with the projecting staples 9 as shown in Figs. 3 and 6 when the locking bar is turned on its pivot for that purpose after the flaps are closed. These hooks may be made to fit within the staples so snugly as to frictionally prevent the bar from being easily disengaged. In order to afford greater security, however, I prefer to have the bar 75 locked in some suitable way. One means of doing this is to form the hooks 13 with holes 14 near their outer ends through which may be passed a wire 15 whose ends may be sealed together by a seal 16 or in some other way.

What I claim is:—

1. A knock-down shipping case or box having four plates which form four sides of the body of the box hinged together and 85 having end closing flaps hinged to the ends of the side forming plates, the end closing flaps being each formed with a sunken panel embossed by a flange raised above the sunken panel, said sunken panels in the respective ends being so formed with relation to each other that when the box is set up and the end flaps are folded upon each other to close the end they will nest together.

2. A knock-down shipping case or box 95 having four plates which form four sides of the body of the box hinged together and having end closing flaps hinged to the ends of the side forming plates, each end closing flap being formed with a sunken panel 100 embossed by a flange raised above the sunken panel, said sunken panels having flaring walls connecting them with said flanges thereby making in the flaps depressions with flaring walls so constructed with relation to 105 each other that when the box is set up and the end flaps are folded upon each other to close the end they will nest together.

3. A knock down shipping case or box 110 made of plates which are corrugated both longitudinally and transversely, said box having four plates which form four sides of the body of the box hinged together and having end closing flaps hinged to the ends of 115 said side forming plates, the corrugations in the end closing flaps being so constructed that when the box is set up and the end flaps closed the corrugations in the several flaps will nest together each with its next adjacent inner flap.

4. A knock down shipping case or box 120 made of plates which are corrugated both longitudinally and transversely, said box having four plates which form four sides of the body of the box hinged together and 125 having end closing flaps hinged to the ends of the side forming plates and the end closing flaps being formed with a sunken panel embossed by a flat flange, the sunken panel being formed with cross corrugations,

transversely and longitudinally, forming pockets the pockets of the several flaps being so constructed that the pockets of each flap will nest with the pockets of the flaps onto which it is folded when the box is set up.

5. A box having end closing flaps adapted to be successively folded one upon another to close the ends, one of said end closing flaps being adapted to be innermost when folded and provided with staple eyes near opposite ends, the others of said end closing flaps being formed with slots through which when folded the eyes of said first folded end flaps are adapted to project outwardly, and 10 a fastening bar pivoted intermediate its ends to the outermost flap, said bar having on its opposite arms hooks which are adapted to engage with the projecting eyes.

6. A box having end closing flaps adapted 20 to be successively folded one upon another to close the ends, one of said end closing flaps being provided with staple eyes near opposite ends and adapted to be the innermost when folded, the others of said end closing flaps being formed with slots through which when folded the eyes of said first folded end flaps are adapted to project

outwardly, and a fastening bar pivoted intermediate its ends to the outermost flap, the bar having on its opposite arms hooks 30 which are adapted to engage with the projecting eyes, and means for locking the hooks into the eyes.

7. A knock-down shipping case or box made of metallic plates hinged together to 35 form the sides and ends of the box, four of said plates being hinged together at their side edges in endless series to form the sides of the box, each side member being hinged at both side edges to the adjacent side members, 40 the others of said plates being hinged to the ends of the side forming plates to form end closing flaps, said end closing flaps being formed with depressed panels so constructed as to adapt all of the end closing flaps for 45 each end to nest together when the box is set up.

In testimony whereof I affix my signature, in presence of two witnesses.
